UNITED STATES PATENT OFFICE.

JAMES ALEXANDER WILLIAMSON, OF PORTADOWN, IRELAND.

SCUTCHING OF FLAX AND LIKE FIBERS.

1,302,261.

Specification of Letters Patent. Patented Apr. 29, 1919.

Application filed June 24, 1918. Serial No. 241,488.

To all whom it may concern:

Be it known that I, JAMES ALEXANDER WILLIAMSON, a subject of the King of Great Britain and Ireland, residing at Portadown, Ireland, have invented certain new and useful Improvements Relating to the Scutching of Flax and like Fibers, of which the following is a specification.

This invention relates to the scutching of flax and like fibers, its object being to provide improvements in scutching mills whereby the cost of scutching may be reduced.

The invention consists in providing, in place of the usual fixed stock, a revolving stock, preferably in the form of a vertical open-topped cylinder having a number of deep notches in its upper edge, each capable of receiving and holding, by suitable clamping, or equivalent means, a bundle of straw, the revolving cylinder being suitably driven so as to take said bundles, one at a time, into position at the usual revolving scutching blades so that the latter can strike the straw against the stock as usual. The relative speed of rotation of the revolving stock and revolving blades is such that each bundle of straw will remain long enough under the action of the blades to knock out the shive or shive against the outer surface of the cylinder. The drive of the revolving stock can be varied to suit the nature of the flax being treated, for example, a comparatively quick drive may be given when soft flax is being dealt with, and a comparatively slow drive when the mill is dealing with hard flax.

The clamping means for holding the flax on the stock during treatment may be so made and operated that each bundle of flax will be automatically released after treatment of one end, and at a convenient point, so that the attendant may reverse the straw for treatment of the other end of the bundle or for the removal of the bundle if both ends have been treated.

The flax or other straw bundles may be held in position on the revolving stock in holders which are also turned by suitable mechanism so as to present all the sides of the bundle of straw to the scutching blades, thus insuring uniformity of treatment.

In order that the invention may be clearly understood I have hereunto appended drawings which show, by way of illustration or example, a rotary scutching stock in accordance with my invention.

Figure 1 is a side elevation, part being

cut away to show the automatic device for turning the bundle of flax to present both sides to the action of the scutching blades and which is also arranged to release the flax at a given point after both sides have been scutched, for the purpose of reversing the bundle of flax in the holder to present the untreated portion to the scutching blades or for the purpose of taking out the scutched bundle and replacing it by a bundle awaiting scutching.

Fig. 2 is a detail view showing how the scutching blade beats the flax on the face of the revolving stock.

Fig. 3 is a horizontal section of the machine on the line 1, 1, Fig. 1.

Fig. 4 is a small diagrammatic view showing certain modifications.

Fig. 5 is a horizontal section on the line 2, 2, Fig. 1.

Fig. 6 is a detail view of the turnable flax holder.

Fig. 7 shows a part side elevation of a slightly modified form of the apparatus.

Referring to the drawings:—

The scutching machine, as shown, comprises a supporting framework *a* carrying upper and under brackets *a*¹ and *a*² respectively, between which, on a vertical shaft *x*, is arranged a circular revolving stock, consisting of an open-topped outer cylinder *b* and an open-topped inner cylinder *c* which are secured together, with a space *e* between them, and have each a number of V-shaped notches, or openings *d* in their upper edges the openings *d* in the outer cylinder *b* being in register with the openings *d* in the inner cylinder *c*. In the space *e* between the cylinders a number of slidably arranged clamping bars *f* are provided, corresponding in number to the number of openings *d*. At their top ends the bars *f* have an inverted V-shaped portion *f*¹ the center of the V being in line with the center of the corresponding openings in the cylinders *b* and *c*. The bars *f* have each a roller *f*² at the lower end and they are caused to turn with the cylinders *b* and *c* and during each revolution each bar *f* is from the point 1, (see Fig. 5), caused to rise on to the cam *g* remaining thereon until it reaches the point 2 where it gets a sheer drop. When the bar *f* is raised on the cam *g* the attendant can place the bundle of flax into the corresponding notch or opening *d* and into the holder *h* as will be hereinafter explained and when the bar *f* falls suddenly

at point 2 the bundle of flax in the notch d is gripped firmly between the opposing V-shaped members and held therebetween during the first scutching operation which takes place at point 3 where the revolving blades k are caused to beat or scutch the flax against the outer wall of the cylindrical stock formed by the cylinder b . After passing the point 3 the bar f is caused to rise on a cam l 10 so as to release the grip of the clamp f^1 on the flax and leave it free to be turned by the turning of the holder h , as hereinafter explained, for the purpose of presenting the other side of the bundle of flax to another set of scutching blades m on the other side of the machine and at the point 4 (see Fig. 3). After leaving the point 4 the bar f is again acted on by the cam g which raises it and releases the grip of the clamp f^1 on 20 the bundle of flax which can then be pulled out and reversed if desired for the purpose of scutching the untreated end or portion or, if the whole of the bundle has been treated, for the purpose of removing same and re- 25 placing it by a fresh untreated bundle.

In order to cause the holder h to be opened to receive, or release the flax, as the case may be, on reaching the filling point 1^a, the holder jaw h^1 is slidably supported and provided 30 with an upward projecting member h^2 capable of being engaged by a cam o on the disk p which does not rotate, the cam o being so shaped as to cause the spindle h^3 of the jaw h^1 to be drawn back against the action 35 of a weight n , or equivalent, as the holder approaches the point 1^a whereby the jaws of the holder will be opened to release and (or) receive the bundle of flax, and then, on a continuation of the rotary movement of 40 the revolving stock b , the member h^2 connected with the jaw h^1 , moves clear of the cam o , and the jaw h^1 is, under the reaction of the weight n , caused to move forward to close the jaws of the holder so that the flax 45 is firmly gripped by the holder and, also, as already explained, by the top f^1 of the holding bar f .

The turning of the holder h , after passing the point 3, is effected by providing a tooth 50 wheel q (see detail Fig. 6) on the hollow spindle h^5 of the jaw h of the holder and providing a vertically slidable rack r in engagement with the teeth of the wheel q , so that, when the rack r is forced downward by 55 a cam s , on the disk p , the wheel q will turn the holder h in one direction and to such an extent as to cause the reversal of the side of the bundle exposed for treatment. Two racks r and r^1 and two cams s and s^1 , are 60 preferably provided, as shown, the rack r^1 being raised by the lowering of the rack r so that on approaching the point 1 the rack r will be up and ready for action and when approaching the point 1^b the rack r^1 will be 65 up and ready for action, one or other of the

racks being always up and ready for action to effect the turning of the holder h as described.

The driving of the revolving stock b is, in the example shown, obtained from the spindle or shaft t which carries and rotates the scutching blades k and m . In this case, a belt drive u is used to drive from a cone u^2 on the shaft t to a reversed cone v on the spindle v^1 , and through suitable reducing gears w^1 , w^2 and w^3 , the driving of the vertical shaft x through a toothed wheel x^1 is effected. The stock cylinders b and c are secured to the shaft x .

The blades k and m are shown revolving 80 in the same direction but they may, if desired, be made to revolve in opposite directions, in which case the blades moving upwardly over the face of the stock b would beat the flax upward against a fixed stock 85 z suitably supported above the revolving stock as shown in the small view at Fig. 4. If the latter arrangement is adopted, the holder turning arrangement, above described, is not required, as the downwardly 90 moving blades beat out one side of the bundle of flax and the upwardly moving blades beat out the opposite side. The revolving stock may be cylindrical, or polygonal in shape and may have parallel sides, as 95 shown, or it may taper slightly downward. The rotation or turning of the revolving stock may be intermittent, with pauses as each bundle of flax comes to the scutching point, or points, or the lineal speed of the 100 stock may be varied, or may be variable, during each revolution.

Instead of, or in addition to, the blades or beaters, such as k and m , I may provide 105 blades or beaters y working across the face of the revolving stock, as shown in the small diagrammatic view at Fig. 4, and beating the flax either down or up or down and up, alternately, or otherwise.

In the modified form of the apparatus 110 illustrated at Fig. 7 there is provided in connection with the revolving stock a fixed comb or spreader A having teeth or fingers B . The comb or spreader A is secured at one end to the disk p and at the other end 115 to the framework or other fixed part of the apparatus. The arrangement is such that, as the stock revolves, the bundles of flax contact with the teeth or fingers B which teeth or fingers thereby simulate the action of 120 scutcher's fingers in the feeding of the flax to the scutching blade or blades. If desired, the teeth or fingers B may be capable of a spring movement or may move under spring 125 action.

Having now fully described my invention, what I claim and desire to secure by Letters Patent is:—

1. Flax scutching apparatus having a revolving stock consisting of a plurality of 130

- open-topped cylinders having openings in their upper edges, means coöperating with said openings for holding the flax in place and for releasing same after treatment, 5 means for revolving the stock, scutching blades, and means for operating the scutching blades.
2. Flax scutching apparatus having a revolving stock consisting of a plurality of 10 open-topped cylinders having openings in their upper edges, cam operated means coöperating with said openings for holding the flax in place and for releasing same after treatment, means for revolving the 15 stock, scutching blades, and means for operating the scutching blades.
3. Flax scutching apparatus having a plurality of open-topped cylinders, notches in the upper ends of the cylinders, means for 20 holding the flax in the notches, means for revolving the cylinders, scutching blades, and means for operating the scutching blades.
4. Flax scutching apparatus having a 25 plurality of open-topped cylinders, notches in the upper ends of the cylinders, clamping means coöperating with the cylinders for holding the flax in the notches, means for revolving the cylinders, scutching blades, and means for operating the scutching 30 blades.
5. Flax scutching apparatus having an inner and an outer cylinder, notches in the upper end of the outer cylinder, notches in 35 the upper end of the inner cylinder in alignment with those in the outer cylinder, clamping means for holding the flax in the notches, means for revolving the cylinders, scutching blades, and means for operating 40 the scutching blades.
6. Flax scutching apparatus having a notched revolving stock, slidably arranged clamping bars working in conjunction with the notches, flax holders working in 45 conjunction with the clamping bars, means for revolving the stock, scutching blades, and means for operating the scutching blades.
7. Flax scutching apparatus having a 50 notched revolving stock, slidably arranged clamping bars working in conjunction with the notches, flax holders working in conjunction with the clamping bars and having movable jaws, automatic means for operating the movable jaws, means for revolving 55 the stock, scutching blades, and means for operating the scutching blades.
8. Flax scutching apparatus having a notched revolving stock, slidably arranged clamping bars working in conjunction with 60 the notches, flax holders working in conjunction with the clamping bars and having movable jaws, cam mechanism for automatically operating the movable jaws, means for revolving the stock, scutching blades, and means for operating the scutching blades.
9. Flax scutching apparatus having a notched revolving stock, slidably arranged clamping bars working in conjunction with the notches, flax holders working in conjunction with the clamping bars, means for automatically revolving the flax holders, means for revolving the stock, scutching blades, and means for operating the scutching 65 blades.
10. Flax scutching apparatus having a notched revolving stock, slidably arranged clamping bars working in conjunction with the notches, flax holders working in conjunction with the clamping bars, rack and 70 pinion mechanism for automatically revolving the flax holders, means for revolving the stock, scutching blades, and means for operating the scutching blades.
11. Flax scutching apparatus comprising 75 a supporting framework, upper and under brackets on the framework, a vertical shaft fitted in the brackets, concentric open-topped notched cylinders on the shaft, slidably arranged clamping bars working in conjunction with the notches, flax holders working in conjunction with the clamping bars, means for revolving the cylinders, means for operating the clamping bars, scutching 80 blades fitted in connection with the framework, and means for operating the scutching blades.
12. Flax scutching apparatus comprising 85 a supporting framework, upper and under brackets on the framework, a vertical shaft fitted in the brackets, concentric open-topped notched cylinders on the shaft, slidably arranged clamping bars working in conjunction with the notches, flax holders working in conjunction with the clamping bars, means for revolving the cylinders, means for operating the clamping bars, scutching 90 blades fitted in connection with the framework, and means for operating the scutching blades.
13. Flax scutching apparatus comprising 95 a supporting framework, upper and under brackets on the framework, a vertical shaft fitted in the brackets, concentric open-topped cylinders on the shaft, slidably arranged clamping bars working in conjunction with the notches, flax holders working in conjunction with the clamping bars, means for revolving the cylinders, means for operating the clamping bars, scutching 100 blades fitted in connection with the framework, and means for operating the scutching blades.
14. Flax scutching apparatus comprising 105 a supporting framework, upper and under brackets on the framework, a vertical shaft fitted in the brackets, concentric open-topped cylinders on the shaft, slidably arranged clamping bars working in conjunction with the notches, flax holders working in conjunction with the clamping bars, means for revolving the cylinders, means for operating the clamping bars, fixed comb mechanism working in conjunction with the concentric open-topped cylinders, scutching blades fitted in connection with the framework, and means for operating the scutching 110 blades.
15. Flax scutching apparatus comprising 115 a supporting framework, upper and under brackets on the framework, a vertical shaft fitted in the brackets, concentric open-topped cylinders on the shaft, slidably arranged clamping bars working in conjunction with the notches, flax holders working in conjunction with the clamping bars, means for revolving the cylinders, means for operating the clamping bars, fixed comb mechanism working in conjunction with the concentric open-topped cylinders, scutching blades fitted in connection with the framework, and means for operating the scutching 120 blades.
16. Flax scutching apparatus comprising 125 a supporting framework, upper and under brackets on the framework, a vertical shaft

fitted in the brackets, concentric open-topped notched cylinders on the shaft, slidably arranged clamping bars working in conjunction with the notches, flax holders working 5 in conjunction with the clamping bars, means for revolving the cylinders, means for operating the clamping bars, fixed comb mechanism having a plurality of teeth working in conjunction with the concentric open-10 topped cylinders, scutching blades fitted in connection with the framework, and means for operating the scutching blades.

15. Flax scutching apparatus comprising a supporting framework, upper and under 15 brackets on the framework, a vertical shaft fitted in the brackets, concentric open-topped notched cylinders on the shaft, slidably ar-

ranged clamping bars working in conjunction with the notches, flax holders working in conjunction with the clamping bars, 20 means for revolving the cylinders, means for operating the clamping bars, stationary spreader mechanism fitted to fixed parts of the apparatus and working in conjunction with the revolving cylinders, scutching 25 blades fitted in connection with the framework, and means for operating the scutching blades.

In testimony whereof I affix my signature in presence of two witnesses,

JAMES ALEXANDER WILLIAMSON.
